specification of Letters Patent. Patented Dec. 15, 1914.

Application filed May 21, 1914. Serial No. 839,944.

To all whom it may concern:

Be it known that I, CHARLES B. ULRICH, a citizen of the United States, residing at Houghton, in the county of Houghton and State of Michigan, have invented certain new and useful Improvements in Files, of which the following is a specification.

My invention consists in an improved construction of filing mechanism for use particularly in drawers or cabinets in which papers, documents and other desired matter are to be filed in classified arrangement in substantially vertical position.

In carrying out my invention I employ a plurality of expansible partitions for use in the drawer or casing of the file, which partitions serve in part as separating guides for classifying the contents of the file. These partitions are constructed with a double wall closed at the top, and with the expanding device contained between said walls, so that the outer surfaces of the partition walls are smooth and uninterrupted, and they alone therefore engage the edges 25 of the papers or other matter being inserted in place between adjacent partitions.

The partitions constructed as referred to may be made and used as separate units, or, if preferred, a plurality of such partitions 30 may be used as a built-up unit by connecting the walls of said partitions at their lower edges by means of yielding material to accommodate between said partitions varying thicknesses of matter to be filed. Additional single wall partitions may be inserted 35 between adjacent walls of the connected double wall partitions, and if desired these single wall partitions may be connected at their lower edges with the yielding material connecting said double 40 wall partitions so as to form a plurality of separated filing receptacles between adjacent walls of the double wall partitions. One or more of these single wall partitions 45 may extend in part through or below the yielding material if desired to be engaged by the retaining rod usually employed in filing cabinets, and for such a construction of cabinet is it advisable in using the separate 50 double wall partitions to extend a portion of one or both of the walls of each partition to be engaged by said retaining rod.

In any event it is desirable to retain the partitions in place in the filing cabinet, so that 55 the contents of the file cannot work under the lower edges of the partitions, and thus

leave the partitions so that they are raised to a position in the cabinet or drawer to interfere with closing the cabinet or drawer, and to interfere also with the proper operation of the partitions as the means for separating and classifying the contents of the file.

For filing cabinets in which a retaining rod is not used, the yielding material above referred to as connecting the lower edges of adjacent walls of the double partitions, serves to hold the partitions in proper position in the receptacle since the contents of the receptacle rest upon the yielding material above referred to as connecting the lower edges of adjacent walls of the double partitions.

In carrying out my invention the double partitions above referred to are preferably constructed of thin flexible material such as pressboard, fiber, or thin sheet metal, folded so that the fold will constitute the outer edge of the partition, or sheets of material may be employed having their outer edges secured together, so that the papers or other matter to be filed cannot be inserted between the two walls of any one of the double wall partitions. Any material may be used in making the double wall partitions which will give the partitions sufficient body so that they will retain their proper position to separate the contents of the file and at the same time permit of sufficient flexure of the partitions under the action of the spring device contained between the two walls of each double partition so that the double partitions may expand under the action of such spring device and completely occupy at all times all of the space in the receptacle which is not occupied by the matter filed between the said partitions. Any spring device, as desired, may be used for expanding the double partitions, and with my construction it is not necessary or desirable to employ a follower block of any description for compressing the contents of the file, as this is taken care of automatically at all times by the expanding tendency of the double wall partitions under the action of the spring mechanism contained between the walls of said partitions.

The outer edges of the partitions preferably are provided with index tabs or index 110 label holders for readily indicating the classification of the contents of the file;

and to secure this result I preferably employ a form of index label holder or tab in connection with the double wall partitions, which will besides serving as an indication of the classification arrangement, reinforce and strengthen the joint at the upper edge of the double wall partition.

I also employ a novel construction of reinforcing device for use with filing drawers or receptacles equipped with retaining rods, so that the same device constitutes a reinforcing means for the tongue extending from the partition wall for engagement with the retaining rod, and also reduces the area of contact for the partition walls upon the bottom of the receptacle to a minimum, thus reducing the friction of partitions upon the bottom of the receptacle when the partitions are moved longitudinally thereof.

In carrying out my invention I do not limit myself to any particular form of spring mechanism between the walls of the double partitions; but it is desirable in any event that the spring mechanism employed shall be of such nature and construction that it can be collapsed into a minimum thickness without passing the elastic limit of the spring.

The several drawings illustrating my invention are as follows:

Figure 1 shows a file receptacle in longitudinal sectional view with expandible partitions of the various kinds above referred to in place therein. Fig. 2 is a transverse sectional view of the parts shown in Fig. 1, taken along the line 2—2. Fig. 3 is an enlarged detail view of the reinforcing eyelet mechanism employed in connection with the tongues extending from the partition walls to receive the retaining rod. Fig. 4 shows in an enlarged detail view taken similarly to Fig. 1, the construction employed where single wall partitions are inserted between double wall partitions, having their lower edges connected by the yielding material. Fig. 5 is a view from the left hand of the parts shown in Fig. 4. Fig. 6 shows in a perspective view the reinforcing mechanism shown in Fig. 3, before it is folded around the lower edge of the projecting tongue of the partition wall. Fig. 7 shows in a detail view the construction of tab or index label holder employed upon the upper edge of the partitions; and Fig. 8 shows in a view similar to Fig. 1 a double partition equipped with a different form of spring mechanism from that shown in Fig. 1.

Similar numerals refer to similar parts throughout the several views.

As shown in Figs. 1 and 2 the file casing 1 contains a plurality of double partitions 2 and 2^a, the two walls of each of which are secured together at their outer edges so as to constitute a continuous connection

between the two walls of the partition. This construction may be secured by folding a sheet of the material of which the partitions are made, or by securing together at their outer edges two sheets of said material to form the double wall partition. The material used may be pressboard, vulcanized fiber, thin sheet metal, or any material which has sufficient body or substance to stand as a partition in the receptacle while supported upon the bottom thereof, and at the same time has sufficient flexibility to permit the double wall partition to expand to occupy its portion of the receptacle when nothing is between any of the partitions of said receptacle. Each of the double wall partitions 2 has disposed between its two walls and near the bottom thereof a plurality of springs 3, and each of the double wall partitions 2^a has similarly disposed a plurality of springs 3^a. These springs in Figs. 1 and 2 are shown as of helico-spiral construction so that they may be compressed to a thickness not exceeding the diameter of the wire of which the springs are made. The springs are held in position between the walls of the partition by engaging one of the walls, preferably as indicated in Fig. 2 by passing through two short parallel slits formed through said wall. This makes a means for securing the springs in place which is at once cheap and effective. The diameter of the springs is preferably large relatively to the diameter of the wire from which they are made, so that they will have a wide range of expansion without interfering in any way with compressing the spring into a single plane, and thus each double partition is readily given such a range of expansion that it will fill its portion of the receptacle and still exert sufficient pressure outwardly on the walls of the double partition to securely hold a single sheet of paper in position between the partition and the adjacent partition.

By forming the springs of a comparatively large diameter it is found that two springs of the kind described will operate satisfactorily in connection with each double wall partition. It is not necessary, however, that this number be employed, as for example, when filing papers that are of uniform size, and of substantially the maximum size that the file is intended to receive, a single spring of somewhat larger diameter, centrally disposed between the walls of the double partition, will serve to give the necessary compression to the contents of the file. On the other hand, for some purposes it may be desirable, particularly where the contents of the file are irregular in character and size, to employ additional springs between the two walls of the double partitions as indicated at 5.

Where the file receptacle is provided with a retaining rod, as indicated at 6, such rod is disposed as is usual in the art, somewhat below the bottom of the receptacle in a channel 7. It is desirable to provide each wall of the double partition with a downwardly extending tongue 8, which enters the channel referred to, and this tongue is preferably equipped with a reinforcing device as shown in Fig. 3, although any other desired construction may be employed for engaging the rod if preferred. In the construction shown in Fig. 3, a sheet of metal, 9, formed as indicated in Fig. 6, is used, and the blank thus formed, it will be noted, is provided with an extending elongated tube, 10, on one side, and a corresponding slot, 11, on the other side. The blank is also provided with depressions, 12, extending on opposite sides of slot 11 transversely of the line of fold of the blank. The blank thus made is folded around the lower edge of the tongue 8 and the tube 10 is expanded after passing through the slot 11 so as to securely hold and clamp the plate 9 upon opposite sides of the tongue 8 in the position indicated in Fig. 3.

The elongated tube 10 forms a vertical receiving slot for the retaining rod 6, and the plate 9 extends sufficiently above the lower edge of the body portion of the partition wall so as to reinforce the tongue 8 and prevent it from being bent relatively to the partition wall and readily detached therefrom.

The depressions 12 formed in the blank form outward projections when the blank is in the case as indicated in Fig. 3, so that the entire weight of the partition wall is carried by these projections upon the bottom of the groove or channel 7, the lower edge of the partition wall being purposely cut away so that the body portion of the partition wall is not in contact with the casing. This provides a means for materially reducing the friction of the partition wall upon the receptacle as it is moved longitudinally on the retaining rod 6.

Where the receptacle is not provided with a retaining rod, or where, for any reason, it is not desirable to provide the double partition walls with downwardly extending tongues, or where it is desirable for any reason to have a plurality of the double partitions connected together, the construction indicated at 2^a is employed, in which the double partitions are similar to those already described, with the exception that they are connected at their lower edges by yielding material 14, such as fabric, so that the papers and other matters filed between these partitions rest upon this yielding material 14, and serve to hold the partitions in place in the receptacle.

The connecting material, 14, must be of

yielding nature, so that it may permit the connected partition walls to separate from each other when papers, documents or other matter of any appreciable or considerable thickness are filed between the partition walls, and yet at the same time permit the partition walls to return into engagement with each other under the action of the spring mechanism when the matter filed is removed from between said partition walls. 75

The two arrangements of partitions above described may be used in any desired combination, that is to say—the double partitions may all be employed as separate units, or they may be connected together as described by yielding material, so as to form built-up units, and these built-up units may or may not be provided with retaining tongues, as desired. 80

For use in a filing receptacle in which no retaining rod is employed it is of course necessary that no extending tongues be used in connection with the partitions, and for this construction of receptacle, in addition to the yielding connecting material, it is sometimes desirable to employ intermediate single wall partitions as indicated at 15, which may be connected to the yielding connecting material 14, as shown. 85

While the yielding connecting material 95 14 may be secured to the lower edges of the partitions in any desired manner, as by pasting, gluing or sewing, it is preferable in any event to cut away the yielding material at its central portion, as indicated in Fig. 5, 100 at 16, so that if it is desired to remove double partitions constructed for use in a file without a retaining rod to one provided with such a device, a single wall partition, 17, may be inserted at any desired point between the connected double partitions, each single wall partition being provided with an extending tongue passing through the yielding material at 16 to engage the retaining rod. By this means the connected 110 double partitions are held in place securely against removal.

From the above description it will at once appear that by means of my construction the entire filing receptacle is at all times occupied, either by the expanding partitions alone, or by said partitions and the filed contents of the receptacle. It will also appear that a proper compression is at all times exerted upon the partition walls to hold the contents of the file securely in position without the use of any follower block, or equivalent compression mechanism. In this manner I am able to eliminate the follower block mechanism with all of the undesirable features incident to its operation, without in any way interfering with the capacity and flexibility of the file. 125

The springs when compressed, and the double walls of the partition, occupy no 130

more, if as much room in the receptacle as the follower block mechanism, and in connection with the automatic spring, a degree of flexibility is secured which cannot be secured with any of the rigid compression mechanisms now commonly in use.

With my invention any desired partitions may be separated easily and quickly, to such an extent as to insert between them, if desired, the entire remaining capacity of the file.

With the file substantially as full as any file can be for efficient operation, additional file matter may readily be inserted by separating the adjacent partitions at their outer edges, which could not be accomplished if compression were secured by a follower block adjusted to various positions according to the contents of the file to secure the necessary compression for such conditions to hold the contents securely in place.

By my invention there is no possibility of inserting the filed matter into the spring mechanism, but, on the other hand, the only surfaces between which such matter can be inserted, are smooth and continuous and offer a substantially uniform resistance to the insertion or withdrawal of the contents of the file, indicated at 18.

Each of the double wall partitions, as well as each of the single wall partitions, is preferably provided at its outer edge with an index tab or index label holder 19, formed as indicated in Figs. 2 and 7, from a thin sheet of metal, or other material, folded upon opposite sides of the partition and secured in place by eyelets 20, formed from one wall of the tab or label holder and extending through the partition and other wall of said tab or label holder, and expanded on their outer ends to securely hold the tab or label holder in position, and strengthen the outer edge of the partition. Either a permanent designation or tab may be mounted in or on 19, or an aperture, or apertures 21, may be provided in the walls thereof to disclose an index label which may be inserted between the walls of said holder. As shown in Fig. 8, flat springs 22 may be employed between the two walls of the double partition 2^b to secure the expansion of said partition, instead of the springs of the form shown in Figs. 1 and 2, although the springs shown in Figs. 1 and 2 give more uniform compression.

While the file receptacle shown in Fig. 1 is of the ordinary drawer type and the partitions are shown as resting upon the bottom of the drawer, it will be understood that the construction of expanding partitions is also applicable to receptacles having the outer edges of the partitions at the side of the receptacle instead of at the top, which result would be secured by simply turning

the drawer receptacle indicated in Fig. 1 upon its side. With this style of receptacle the partitions and guides will naturally rest upon the lower side of the receptacle, and to reduce the friction at the bearing points to a minimum, projecting points are formed on the edges of the partitions, as indicated at 23 and 24, which will come in contact with the top or bottom of the receptacle, according to the position of the partitions in the open-sided receptacle and thus prevent the partitions from bearing at more than these points. Additional projecting points 25 are preferably provided at the inner edges of the partitions, so as to prevent the inner edges from bearing on the corresponding side of the receptacle for any position the partitions may assume therein.

Elongated slots in the tongues 8 are provided, so that the partitions may be inclined to a considerable degree to examine the contents of the file at any particular point without causing any binding whatever of the partitions against the retaining rod 6, and in carrying out my invention it will be understood that the spring compression should preferably be a maximum somewhat below the middle of the partitions, as the maximum tendency of the contents of the file to spread the partitions is exerted at that point rather than at some higher point in the file.

While the expandable partitions have been described as provided with auxiliary spring mechanism, of one kind or another, for expanding them to fill the file at all times, it will be understood that these auxiliary spring devices may be dispensed with by constructing the partitions themselves of thin spring material, as thin sheet steel or brass having the proper conformation and the requisite amount of resilience to entirely fill the file at all times.

While I have shown my invention in the particular embodiments described, it will be understood that I do not limit myself to these constructions, but that I may use any equivalents of these devices without departing from the spirit of my invention.

What I claim is:

1. In a file, the combination of a receptacle open at one side, and a plurality of expanding double wall partitions resting upon one of the walls of said receptacle, the outer edges of said double walls of each partition being closed to prevent inserting papers and other matter between said walls of any partition.

2. In a file, the combination of a receptacle, a plurality of double wall partitions in said receptacle, the walls of each partition being joined at their outer edges, and spring mechanism carried by each of the partitions between its walls tending to expand said partitions.

3. In a file, the combination of a recep-

- 5 tacle open at one side, a plurality of expanding double wall partitions resting upon one of the walls of said receptacle, the outer edges of said double walls of each partition being closed to prevent inserting papers and other matter between said walls of any partition, and a retaining rod carried by the receptacle and engaging said partitions to prevent their removal from said receptacle.
- 10 4. In a file, the combination of a receptacle, a plurality of double wall partitions in said receptacle, the walls of each partition being joined at their outer edges, spring mechanism carried by each of the partitions 75 between its walls tending to expand said partitions, tongues extending from said partitions, and a retaining rod carried by said receptacle and engaging said tongues.
- 15 5. In a file, the combination of a receptacle open at one side, a plurality of expanding double wall partitions resting upon one of the walls of said receptacle, the outer edges of said double walls of each partition being closed to prevent inserting 80 papers and other matter between said walls of any partition, and a retaining rod carried by the receptacle and extending through both walls of each partition.
- 20 6. In a file, the combination of a receptacle, a plurality of double wall partitions in said receptacle, the walls of each partition being joined at their outer edges, a tongue extending from each wall of each partition, and a retaining rod carried by the 85 receptacle and passing through said tongues.
- 25 7. In a file, the combination of a receptacle, a plurality of double wall partitions in said receptacle, the walls of each partition being joined at their outer edges, spring mechanism carried by each of the partitions between its walls tending to expand said partitions, tongues extending from said partitions, a retaining rod carried by the 90 receptacle and engaging said tongues, and a member carried by each tongue for reinforcing the rod opening and stiffening said tongue.
- 30 8. In a file, the combination of a receptacle, a plurality of double wall partitions in said receptacle, the walls of each partition being joined at their outer edges, a tongue extending from each wall of each partition, a retaining rod carried by the 95 receptacle and passing through said tongues, and a metallic member folded around each tongue to stiffen said tongue and form a reinforced edge around the rod opening in said tongue.
- 35 9. In a file, the combination of a receptacle, a plurality of double wall partitions in said receptacle, the walls of each partition being joined at their outer edges, a tongue extending from each wall of each partition, a retaining rod carried by the 100 receptacle and passing through said tongues, and a metallic member folded around each tongue to support the weight of the partition from the receptacle and reduce the friction of said partition thereon.
- 40 10. In a file, the combination of a receptacle, a plurality of double wall partitions in said receptacle, the walls of each partition being joined at their outer edges, a tongue extending from each wall of each partition, a retaining rod carried by the 105 receptacle and passing through said tongues, and a metallic member folded around each tongue, said member having a tubular extension from one wall extending through said tongue and expanded on the opposite side of the other wall of said member, the bore of said extension affording a clearance around the retaining rod sufficient to permit inclining the partition walls to inspect the contents of the file, said member extending onto the body portion of the partition wall to prevent bending of the tongue relatively thereto.
- 45 11. In a file, the combination of a receptacle, a plurality of double wall partitions in said receptacle, the walls of each partition being joined at their outer edges, a tongue extending from each wall of each partition, a retaining rod carried by the 110 receptacle and passing through said tongues, and a metallic member folded around each tongue, said member having a tubular extension from one wall extending through said tongue and expanded on the opposite side of the other wall of said member, the bore of said extension affording a clearance around the retaining rod sufficient to permit inclining the partition walls to inspect the contents of the file, said member extending onto the body portion of the partition wall to prevent bending of the tongue relatively thereto, said member having beads on its folded edge to engage the adjacent surface of the receptacle.
- 50 12. In a file, the combination of a receptacle, and a plurality of double wall partitions in said receptacle, the walls of each partition being joined at their outer edges and having spring material between other portions tending to expand said partitions.
- 55 13. In a file, the combination of a receptacle, a plurality of double wall partitions in said receptacle, the walls of each partition being joined at their outer edges, and helical springs contained in said partitions and secured thereto.
- 60 14. In a file, the combination of a receptacle, a plurality of double wall partitions in said receptacle, the walls of each partition being joined at their outer edges, and helical spiral springs contained in said partitions.

- titions and secured thereto to collapse into the thickness of the wire of said springs.
15. In a file, the combination of a receptacle, and a plurality of double wall partitions in said receptacle, the walls of each partition being joined at their outer edges and having spring material between other portions tending to expand said partitions, said partitions being of flexible material of sufficient body to support themselves by resting at their inner edges on said receptacle.
16. In a file, the combination of a receptacle, a plurality of double wall partitions in said receptacle, the walls of each partition being joined at their outer edges and having spring material between other portions tending to expand said partitions, and a yieldable connection between lower edges of adjacent partitions.
17. In a file, the combination of a receptacle, a plurality of double wall partitions in said receptacle, the walls of each partition being joined at their outer edges and having spring material between other portions tending to expand said partitions, a yieldable connection between lower edges of adjacent partitions, and a single wall partition between adjacent double wall partitions and secured at its lower edge to said yieldable connection.
18. In a file, the combination of a receptacle, a plurality of double wall partitions in said receptacle, the walls of each partition being joined at their outer edges and having spring material between other portions tending to expand said partitions, a yieldable connection between lower edges of adjacent partitions, a single wall partition between adjacent double wall partitions, said single wall partition having a tongue extending below said yieldable connection, and a retaining rod engaging said tongue to hold said single wall partition and the adjacent double wall partitions in said receptacle.
19. In a file, the combination of a receptacle, a plurality of double wall partitions in said receptacle, the walls of each partition being joined at their outer edges and having spring material between other portions tending to expand said partitions, and an indexing device secured to the upper edge of each partition.
- 55 20. In a file, the combination of a receptacle, a plurality of double wall partitions in said receptacle, the walls of each partition being joined at their outer edges and having spring material between other portions tending to expand said partitions, and an indexing device extending downward on both sides of each partition and provided with eyelets formed from one side of said device and extending through the partition and clenched on the other side of said de-
- vice, said device extending above the partition and forming an indexing means.
21. A partition for a file, comprising a double wall of flexible material, the outer edges of the walls being joined together and having spring material between other portions tending to expand said partition.
22. A partition for a file, comprising a double wall of flexible material, the outer edges of the walls being joined together and having spring material between other portions tending to expand said partition, and a tongue extending from one of said walls to engage a retaining rod.
23. A partition construction for files, comprising a plurality of double wall partitions, the walls of each partition being joined at their outer edges and having spring material between other portions tending to expand said partition, and yieldable material connecting the free edges of adjacent partitions.
24. A partition construction for files, comprising a plurality of double wall partitions, the walls of each partition being joined at their outer edges and having spring material between other portions tending to expand said partition, yieldable material connecting the free edges of adjacent partitions, and a partition between adjacent walls of said partitions and having a projecting tongue to engage a retaining rod, said connecting material being cut away to permit said tongue to project therethrough.
25. A partition for files, comprising a double wall of flexible material, the outer edges of said walls being joined together, and a helical spring disposed between said walls and connected to said partition.
26. A partition arrangement for files, comprising the combination of a plurality of double wall partitions of flexible material, the walls of each partition being joined at their outer edges, a helical spring between the walls of each partition and connected to said partition, and yieldable connecting material between the free edges of the walls of adjacent partitions.
27. A partition for files, comprising a sheet of material having a projecting tongue, and a reinforcing device for said tongue folded around its outer edge and having a tube formed from one of its walls extending through said tongue and the opposite wall of said device and expanded to clamp said device in engagement with said tongue, said device extending beyond the tongue to the body portion of said sheet to stiffen and reinforce the connection of said tongue to said sheet.
28. A partition for files, comprising a sheet of material having a projecting tongue, and a reinforcing device for said tongue folded around its outer edge and having a tube formed from one of its walls

extending through said tongue and the opposite wall of said device and expanded to clamp said device in engagement with said tongue, said device extending beyond the tongue onto the body portion of said sheet to stiffen and reinforce the connection of said tongue to said sheet, said device having a projecting bead on its folded edge to bear against the adjacent surface of the receptacle containing said partition.

29. A partition for a file, comprising a sheet of material provided on its supporting edge with a rounded projection for free sliding engagement upon a containing receptacle.

30. An index device for use with partitions of a file comprising a sheet of material folded so as to extend upon opposite sides of the partition and project beyond the outer edge of the same, one of the walls of said device having one or more eyelets formed therefrom and extending through the partition and through the other wall of said device and expanded on the outer side thereof to hold said device in place and reinforce the outer edge of said partition.

31. An index device for use with partitions of a file comprising a sheet of material folded so as to extend upon opposite sides of the partition and project beyond the outer edge of the same, one of the walls of said device having one or more eyelets formed therefrom and extending through the partition and through the other wall of said device and expanded on the outer side thereof to hold said device in place and reinforce the outer edge of said partition, said device having an opening in its projecting portion to disclose the classifying character or legend carried thereby.

32. A partition for a file, comprising a double wall of flexible material, the outer edges of the walls being joined together, and said partition having a spring construction tending to separate said walls from each other.

33. A partition for a file, comprising a double wall of flexible material, the outer edges of the walls being joined together, said partition having a spring construction 50 tending to separate said walls from each other, and a tongue extending from one of said walls to engage a retaining rod.

34. A partition construction for files, comprising a plurality of double wall partitions, the walls of each partition being joined at their outer edges and each partition having a spring construction tending to separate its walls from each other, and yieldable material connecting the free edges 60 of adjacent partitions.

35. In a file, the combination of a receptacle, and a plurality of double wall partitions in said receptacle, the walls of each partition being joined at their outer edges 65 and each partition having a spring construction tending to separate its walls from each other.

36. In a file, the combination of a receptacle, a plurality of double wall partitions 70 in said receptacle, the walls of each partition being joined at their outer edges and each partition having a spring construction tending to separate its walls from each other, a tongue extending from each wall of 75 each partition, and a retaining rod carried by the receptacle and passing through said tongues.

37. A partition for a file, comprising a sheet of material provided on its supporting 80 edge with a plurality of rounded projections for free sliding engagement upon a containing receptacle.

38. A partition for a file comprising a sheet of material provided on its bearing 85 edges with rounded projections for free sliding engagement upon a containing receptacle.
